(57) **CLAIM**

The ornamental design for a decorative reflective spinning ornament, as shown and described.

DESCRIPTION

FIG. 1 is a side elevational view of the decorative reflective spinning ornament showing my design, the opposite side elevational view being a mirror image;

FIG. 2 is a top plan view thereof;

FIG. 3 is a bottom plan view thereof;

FIG. 4 is a perspective view thereof;

FIG. 5 is a side elevational view of a second embodiment thereof, the opposite side elevational view being a mirror image;

FIG. 6 is a top plan view of a second embodiment thereof;

FIG. 7 is a bottom plan view of a second embodiment thereof;

FIG. 8 is a perspective view of a second embodiment thereof;

FIG. 9 is a side elevational view of a third embodiment thereof, the opposite side elevational view being a mirror image;

FIG. 10 is a top plan view of a third embodiment thereof;

FIG. 11 is a bottom plan view of a third embodiment thereof; and,

FIG. 12 is a perspective view of a third embodiment thereof.
